UNITED STATES PATENT OFFICE.

SAMUEL W. MARTIN, OF SPRINGFIELD, OHIO, ASSIGNOR TO THE MAST,
FOOS & COMPANY, OF SAME PLACE.

CENTERING AND TIGHTENING DEVICE FOR WINDMILL-TOWER BRACES.

SPECIFICATION forming part of Letters Patent No. 591,860, dated October 19, 1897.

Application filed August 28, 1896. Serial No. 604,175. (No model.)

To all whom it may concern:

Be it known that I, SAMUEL W. MARTIN, a citizen of the United States, residing at Springfield, in the county of Clark and State 5 of Ohio, have invented certain new and useful Improvements in Centering and Tightening Devices for Windmill-Tower Braces, of which the following is a specification, reference being had therein to the accompanying 10 drawings.

This invention relates to certain new and useful improvements in a centering and tightening device for windmill-tower braces.

The object of my invention is to provide a 15 device which can be applied to the braces of the modern windmill-tower in the acute or in one angle as distinguished from two opposite angles formed by such braces, so that when said device is forced toward the intersection 20 of the braces it will cause either or both of the braces to so shift that they will be made to finally cross one another at a point in the center line of the tower, and in doing which the least taut of the braces will shift and become 25 itself strained or tightened, equally with the other brace, and their tension and effects on the tower be equalized.

To this end my invention consists of two plates or disks and a connecting-bolt adapted 30 to draw them together, combined with the intersecting windmill-tower braces and applied to them in the acute or in one angle formed thereby.

In the accompanying drawings, forming a 35 part of this specification, and on which like reference-letters indicate corresponding parts, Figure 1 represents a side elevation of a windmill-tower with my invention applied thereto; Fig. 2, a detail enlarged diametrical sectional 40 view of the center and tightening device; Fig. 3, an enlarged elevation of such device and two of the braces combined therewith; Fig. 4, a plan view of one of the plates or 45 disks, and Fig. 5 an edge view or elevation of two braces and my said device.

The letter A designates one type of modern windmill-tower, made of iron or steel and composed of beams B, cross-bars C, a platform D of wood, and cross-braces E and F. 50 These braces are flattened at their ends, as

seen at G, and are bolted to the tower by bolts H, which pass through the overlapped ends of the braces and through holes in the beams B.

In manufacturing such towers the braces E and F are intended to be punched or bored 55 both alike as to each pair, so that the holes should be the same distance apart; but in their rapid production it frequently happens that there is a variance of one-fourth to three-eighths of an inch in the distance between the 60 holes in one brace and the distance between the holes of the other brace which is to work with it. This is not noticed or discovered until the tower is being erected at the place 65 of use.

To bring the holes of the tower-braces one over the other so that the bolt will go through, one brace will be slightly slackened and diverted to one side, so that it will not intersect with the other brace in the central line 70 of the tower. Or it sometimes happens that the beams B of the tower are sprung in a little to bring the hole in it in line with the hole in the shorter of the two braces. This springs the tower-beam out of a straight line somewhat. Hence my object is to take up this slack in the braces, and to make the braces finally intersect in line with the center line of the tower; and doing this also so acts on the 75 braces that the slight bending or deflecting of the tower-beam will be overcome and the beam sprung or restored back to its true line. These effects I have accomplished by means

of combining with the intersecting or crossing braces, in the acute angle formed by them, 85 my centering and tightening device. This device consists of two plates or disks I and J, each having a raised or extended boss or portion K, and a receding or lower surface L, and a central opening M for a connecting- 90 bolt O. The bosses K are each provided with a stud P and a socket Q, so that the stud of one boss will fit into the socket of the other boss, and thereby hold the plates or disks in their proper relative positions to form the 95 space between the surface L of one plate or disk and the boss of the other. Such a space is formed on each side of the disks or plates, and in one of these spaces one of the braces fits and in the other of them the other brace 100

fits. This is clearly seen in the drawings. Now, after the tower has been erected, for the purpose above stated, I apply my centering and tightening device to a pair of intersecting braces by placing the same in an acute angle formed thereby, with the braces in the spaces between the surface L and the boss K. The nut R on the bolt O is at this time slightly slackened, and then the foot of the builder or 10 erector of the tower is placed on the device and it is forced down (or up if applied to the lower acute angle) as far as it will go. The more slack of the two braces shifts sidewise until it becomes equally taut with the other, 15 and then both yield equally and bring their point of intersection in line with the center of the tower. This equalizing of the strain of the two braces restores also the tower beam or beams from the deflection, more or less, it 20 or they have suffered in springing to accommodate the variance in the distance between the holes in the braces. When the device is thus forced to its limit, the braces refuse to yield to the pressure, the nut R on the bolt 25 O is screwed up tight, and the plates or disks made to firmly clamp each of the braces.

Referring again to the bosses K, it will be seen that they form a shoulder K', which slides against the inner edges of the braces.

30 While I have shown and described my centering and tightening device in combination with the braces of a windmill-tower, it is obvious that should similar braces be used on bridges or other structures the device would 35 be applicable.

I have also shown my device as applied to the acute angle formed by the braces; but it is obvious that it is applicable to one angle as distinguished from two angles, whether 40 such angle be acute or not.

Having thus fully described my invention,

what I claim as new, and desire to secure by Letters Patent, is—

1. The combination with the intersecting braces of a windmill-tower, of a centering and 45 tightening device consisting of a pair of plates or disks fitted one upon the other in one of the angles and between the braces and having shoulders which fit against and embrace the braces, and a bolt to tighten and hold the 50 parts together.

2. The combination with a windmill-tower and its intersecting braces, forming an acute angle between them, of a centering and tightening device consisting of a pair of plates or 55 disks each having a boss forming a shoulder and a receding face, and a socket and stud matching a socket and stud of the other, and a bolt to bind the plates against the braces when the same are fitted in the acute angle. 60

3. A centering and tightening device, consisting of a pair of plates or disks each having a receding face and a boss forming a shoulder, the receding face of one plate or disk being opposite the boss of the other plate or disk, 65 and each having a central opening, and a bolt fitted in said opening to bind the parts together.

4. A centering and tightening device consisting of a pair of plates or disks, each having 70 a receding face extending partly around it, a boss occupying the rest of the surface, a stud on the boss and a socket in it and a central hole in the boss, the plates or disks being interlocked by the studs and sockets, and a bolt 75 in the opening to bind the parts together.

In testimony whereof I affix my signature in presence of two witnesses.

SAMUEL W. MARTIN.
